US0D1114158S

(12) **United States Design Patent** (10) **Patent No.:** **US D1,114,158 S**
(45) **Date of Patent:** **** Feb. 17, 2026**

(54) **GAS BAG FOR TURBINE OR THE LIKE**

(71) Applicant: **AEROTEST LIMITED**, Hemel Hempstead (GB)

(72) Inventor: **Mike Bruce**, Hemel Hempstead (GB)

(73) Assignee: **AEROTEST LIMITED**, Hemel Hempstead (GB)

(**) Term: **15 Years**

(21) Appl. No.: **29/948,218**

(22) Filed: **Jun. 20, 2024**

(30) **Foreign Application Priority Data**

Dec. 21, 2023 (GB) 6334889

(51) **LOC (15) Cl.** **12-16**

(57) **CLAIM**

The ornamental design for gas bag for turbine or the like as shown and described.

DESCRIPTION

FIG. 1 is a front elevation view of a gas bag for turbine or the like showing the new design;

FIG. 2 is a rear elevation view thereof;

FIG. 3 is a right side elevation view thereof;

FIG. 4 is a left side elevation view thereof;

FIG. 5 is a top plan view thereof; and,

FIG. 6 is a bottom plan view thereof.

The broken lines depict portions of the gas bag for turbine or the like that form no part of the claimed design.

1 Claim, 6 Drawing Sheets
